UNITED STATES PATENT OFFICE

HARRY E. VON KERSBURG, OF SCARSDALE, NEW YORK, ASSIGNOR TO R. H. MACY & CO., INC., OF NEW YORK, N. Y., A CORPORATION OF NEW YORK

KEY UNIT

Application filed January 13, 1928. Serial No. 246,439.

The present invention relates to a "key unit" or key filing cabinet, or in other words a cabinet in which the locker keys are hung up and stored when not in use by the numerous employees of a business establishment, and for which purpose individual key-hooks are provided upon which perforated tags in different colors are hung, indicating the various classes of occupants of the lockers and 10 the unoccupied lockers.

The invention further consists in the combinations and arrangements of elements hereinafter described and particularly set forth in the accompanying claim.

An object of the invention is to so construct and furnish the cabinet that all sections thereof are easily and equally accessible for the purpose set forth, at the same time giving it a neat appearance and assuring a 20 safeguard against locker keys getting into possession of unauthorized persons.

Furthermore, the cabinet is so arranged that the custodian thereof may at a glance ascertain which of the lockers are occupied 25 and the class of the respective lockers.

The use of the cabinet is evidently not limited to workmen in a factory or employees in a store, but it is also suitable for keeping the keys for the rooms in a large office building, apartment house, hotel, and so forth.

In the accompanying drawing one embodiment of the invention is illustrated, and:

Figure 1 is a front elevation of the cabinet open;

Figure 2 a vertical sectional view taken along line 2-2 of Figure 1;

Figure 3 a fragmentary sectional view taken along line 3-3 of Figure 2;

Figures 4 and 5 are fragmentary sectional views in larger scale taken along lines 4-4 and 5-5 of Figures 2 and 1, respectively;

Figure 6 is a view similar to Figure 3, showing the cabinet as built of metal exclusively; and,

Figure 7 shows a colored tag.

Referring now to the drawings in which the same reference characters refer to the same parts in the different views, reference numeral 7 represents a cabinet of the class described and which in Figures 1 and 2 has

been shown as a double-deck or two-story key-unit, but which may, of course, contain several more stories or only one, in accordance with special requirements.

The cabinet has an open front, side walls 55 8, rear wall 9, top 10, and bottom 11; and when built in several stories has also intermediate floors 12, in this manner providing superimposed compartments or chambers.

On the upper side of the bottom 11 and the 60 underside of the top 10 are provided parallel grooves 13 and 14, respectively, running in the length direction of the cabinet and opening into the face or open end thereof. Similar and corresponding grooves 15 and 16 are 65 also found on the upper and lower sides of the floor member 12. These grooves form guide-ways for sliding uprights 17 which are permitted to have limited forward and rearward movements in the cabinet. For this 70 reason stops are provided which preferably consist of studs or dowels 18 driven into the bottom 11 and floor 12 adjacent to the cabinet opening and corresponding pins or pegs 19 near the bottom edge of the uprights 75 17.

On the forward or outer edge of each upright is hinged as at 20 a panel 21 adapted to swing, as indicated by dotted lines in Figure 3, in both directions, out of the plane of 80 the grooves or the upright 17 where the panel together with its upright is drawn out of the compartment. Accordingly, it has been so arranged that when the stops 18, 19 contact, the hinges of the panel have just emerged 85 from the cabinet as best seen in Figures 2 and 3. Either hook and eye or leaf-hinge 20 may be used.

To facilitate the sliding out of the panel and its upright, a handle 22 is secured to the outer edge of the panel 21. On each side of the panel are arranged a series of hooks 23 each adapted to receive a key. Where not shown fully in the figures they are indicated by crosses, each panel to have hooks to accommodate from fifty (50) to one hundred (100) keys. They are preferably placed in parallel rows and may be numbered consecutively or marked in some other suitable manner for identification.

A door 24 adapted to close the opening of the cabinet is shown hinged as at 25 to the bottom 11 thereof in such a manner that it will remain horizontal when open (see Figure 2) and form a service table for the custodian of the cabinet. Instead of being hinged to the bottom, this door may be hinged to one side of the cabinet to swing in horizontal instead of vertical direction; or it may be flexible or constructed as a roll-curtain door.

10 The door is provided with latch 26 or regular lock to keep the cabinet locked so that the keys are under control of the custodian.

15 The cabinet is mounted on a suitable stand or regular filing form 27 preferably provided with a flat top 28 which projects in forward direction of the cabinet in order to form a support for the door 24 when it is open and serves as a table, as best seen in Figures 1 and 2.

20 The cabinet as described above is intended to be built mainly of wood. For offices in general and as protection against fire, an all-metal construction is preferable and is illustrated in Figure 6.

25 The body 30 of the cabinet comprising sides, back, top, bottom, and floors are here shown made of single sheet metal, but may of course also have double sheeting which then would be spaced apart to provide air spaces. Around the front opening the sheet metal is folded back as at 31 to furnish a hook member. This engages with a corresponding hook member 32 of a two-ply reinforcing facing or casing 33 surrounding the entire opening of the cabinet and projecting forwardly of the body 30. In this manner an offset is formed between the inner surfaces of the body and the corresponding ones of the casing as clearly shown in the figure.

30 The grooves or guide-ways 34 are in this instance formed by corrugating the top and bottom 35 of the cabinet body 30 or by using separate channels secured thereto. As before uprights 36 are adapted to engage and slide in the top and bottom guide-ways but instead of being made solid they are preferably hollow as indicated. The stops 18 for limiting the sliding movement are here secured in the casing 33 and adapted to engage with corresponding pegs 19 on the uprights 36. In this case a metal door is hinged to the front edge of the casing.

35 Double acting hinges 37 connect as before the front edge of the sliding upright with the corresponding panel 38 to permit the latter to swing in both directions out of the vertical plane of the upright. The panel is here constructed of a channel-shaped metallic frame 39, in the grooves of which is held firmly a board 140 of sheet metal. On this board are fixed a series of hooks 23 projecting from both sides of the board, each panel carrying individual hooks for fifty (50) to one hundred

40 (100) keys, or any other number required.

As before, the hooks are preferably numbered or given some distinguishing mark so that the keys may be easily located. A handle 22 is fastened on the forward edge of the frame 39.

45 A stand 27 is also in this case provided for the cabinet but made of metal instead of wood.

With the panels lettered or labeled and the key hooks numbered it will now be very easy to locate the hook for the key desired. After the door 24 has been opened, one of the panels carrying the correct designation is next drawn out by gripping handle 22. The panel is thereupon swung to the right or the left depending on which side the particular hook 23 is located for the desired key. After all the keys needed have been removed, the panels are pushed back in their respective guide-ways and the door 24 again closed and locked by the custodian.

50 An important feature of the invention is the manner of indicating the character of the occupancy of the lockers to which the keys belong. For this purpose the hooks 23 also carry tags 40 to indicate whether the locker, to which a particular key belongs, is occupied or unoccupied, and also the class of its occupant. The tags have accordingly different colors or may carry other distinguishing marks (see Figure 7).

55 It is understood that the invention is not limited to the details of construction here shown and described, but that these may be varied widely without departing from the spirit of the invention as defined by the claim.

60 What I claim as new is:

A sheet metal cabinet having superposed compartments and an open front, vertical panels mounted in each of said compartments, each of the said panels being hingedly mounted on a hollow upright, and a door hinged to the bottom of said cabinet for closing both compartments; the metal around the open front of the cabinet being reversely bent to form an open channel in which is engaged a projecting reinforcing casing offset from the side of said cabinet, the said cabinet having longitudinal grooves formed in the top and bottom sides thereof in which said uprights are adapted to slide, the said panels comprising frame members having inturned edges to form inwardly facing grooves in which are mounted integral metal panels.

In witness whereof, I have hereunto set my hand at New York city, New York, this 6th day of December, A. D. nineteen hundred and twenty-seven.

65 HARRY E. VON KERSBURG.
